(57) **CLAIM**

The ornamental design for a file organizer, as shown and described.

DESCRIPTION

FIG. 1 is a front perspective view of a file organizer;

FIG. 2 is a front elevation view thereof;

FIG. 3 is a rear elevation view thereof;

FIG. 4 is a top view thereof;

FIG. 5 is a bottom view thereof;

FIG. 6 is a right side view thereof; and,

FIG. 7 is a left side view thereof.

The short and long dash broken lines and evenly spaced broken lines immediately adjacent the shaded areas depict the bounds of the claimed design, while all other broken lines are directed to environment. The broken lines form no part of the claimed design.

The broken away symbols in the drawings indicate that the appearance of any portion of the article between the break lines forms no part of the claimed design.
